UNITED STATES PATENT OFFICE.

ERNEST T. JOHNSON, OF JAMESTOWN, NEW YORK.

BUILDING CONSTRUCTION.

Application filed November 24, 1926. Serial No. 150,610.

This invention relates to an improvement in building construction and more particularly to door, partition sash and window frames, wholly or partially of sheet metal.

Such constructions have, prior to this invention, been of two distinct types. The original type comprises three elements: first the buck by which the opening is defined; second a jamb which receives the door or sash; third trim connecting the jamb and walls providing a finish to the opening. The later type comprises the three elements formed into an integral unit, known in the trade as combination buck, jamb and trim, built into place by the masonry construction.

The primary object of this invention is to substitute for these prior constructions, a construction consisting of two elements, one of which will function both as buck and trim, and the other will form the jamb or hanging strip for receiving door or sash, and to which the hardware in general is secured.

A further object of this invention is to provide a construction by which the erection of a building is in no way delayed, and by which the assortment of hardware, the action and form of mounting of door or sash can be selected at random, and can be altered at will without injury to the building walls, or without necessitating any alteration of the door frame proper.

Another object of this invention is to provide a single element which may be termed a combination buck and trim, and in which is provided a recess to house removably a jamb or hanging strip.

Other objects of this invention will appear from a consideration of the following description taken in connection with the drawings which form a part thereof, and in which

Fig. 1 is a front elevation of a doorway embodying this invention;

Fig. 2 is a perspective view of the bottom of the doorway, illustrating the manner of securing spreaders to the frame uprights;

Fig. 3 is a perspective view of portions of the spreaders showing the manner in which they are inter-engaged;

Fig. 4 is a perspective view of a jamb or hanging strip, which forms one element of this invention;

Fig. 5 is a perspective view of a retaining strip, to which hardware is secured;

Fig. 6 is a side elevation of a corner of a

frame, parts being broken away to show the means for uniting the upright to the top;

Fig. 7 is a perspective view on a large scale of a portion of the upright and top shown in Figure 6;

Fig. 8 is a perspective view of the plate connecting the upright and top member;

Fig. 9 is a plan view of the top member;

Fig. 10 is a perspective view, partly in section, illustrating one embodiment of this invention;

Figs. 11, 12 and 13 are sectional views illustrating various types of doors and jambs, and indicating some of the ways in which this invention can be employed;

Fig. 14 is a perspective view of a wooden jamb embodying this invention;

Fig. 15 is a sectional view taken along the line 15—15 of Fig. 14, and

Fig. 16 is a perspective view of an anchor plate used in the form shown in Figures 14 and 15.

In the erection of modern buildings the door frames are required as soon as the outside walls, and the floors are in, and prior to the building of the partition walls. This condition of course arises long before the doors are hung and long before it is customary to decide on the hardware and the action and forms of mounting the doors. Numerous instances have arisen in which the continuation of construction of modern buildings has been greatly delayed before the architects have decided all these details and until the door frames have been constructed in accordance with these decisions.

This invention avoids such delay by a construction, embodiments of which are set forth in the drawings above described, which show the invention as applied to doorways. It will, of course, be understood that this invention is applicable to frames for openings in buildings other than doorways which have been selected for the purpose of illustration and not of limitation.

Referring to the drawings, the reference numeral 20 is employed to designate a doorway embodying one form of this invention, which doorway comprises a combination buck and trim 21, hereinafter referred to as a frame, and a jamb 22, which is removably secured thereto. The frame 21 is connected by means of anchors 23 to the walls 24 of the building in the usual manner. The frame

21, as is customary, extends below the floor 25 of the building and the uprights are connected by means of spreaders 26. These spreaders are provided with central notches 27, so that they can cross each other in the manner shown in Figures 2 and 3, and are rigidly secured to the uprights, thus fixing them in the proper position.

The entire frame 21, but particularly the 10 central portion thereof, functions as a buck while the sides 28 constitute the trim, which extends in the usual manner at each side of the wall 24, and which may be of any desired contour. In the central portion of the frame 15 is formed a recess 29, defined by parallel flanges 30, which houses removably the jamb 22 in any suitable manner, as for example, that described hereinbelow.

The anchors 23, which may be of the usual 20 corrugated type, are secured to the buck 21 by means of integral tongues 31, which extend through slots 32 in the recess 29. A washer 33 is slipped over the tongues after they project through the slots 32 and the 25 tongues 31 are then bent back to fix the anchors 23 in position. The slots 32 extend longitudinally, thus permitting adjustment of the anchors to suit the construction of masonry, which is built around the frame. Integral clips 34 project upwardly from the 30 base of the recess 29, and terminate in rounded noses 35, (see particularly Figure 10).

The frame 21 is made up of uprights 36, and a top 37, which may be joined to the 35 uprights by miter joints 38. The joiners of the uprights and top are reinforced and the frame is braced by means of angle plates 39, which enter integral straps 40 formed in the uprights and top near the joints.

40 Each jamb 22 is provided with sides 50, which terminate in flanges 51 parallel to the body portion of the jamb. The flanges 51 are connected to the sides 50 by inclined portions 52. Each jamb 22 is removably secured 45 in a recess 29 of the frame 21 by forcing the flanges 51 of the jamb beyond and beneath the noses 35 of the clips 34. By reason of the inclined portions 52 the flanges will slide under the noses 35 of the clips 34 without 50 difficulty. The sides 50 rest against the inner faces of the walls 30 so that the jamb 22 is fixed firmly but removably in the recess 29.

Each jamb 22 is provided with a door stop 53 of the form required by the type of door 55 to be installed. The stop 53 is preferably made integral with the jamb when the latter is of sheet metal. Upon the jambs 22 are fixed the necessary hinges, strike plates and other hardware. By providing mortises 54 60 in the jamb 22 a leaf 55, forming part of the hinge 56, may be secured to said jamb, this being particularly shown in Figs. 4 and 10. Reinforcing plates 57 are secured to the back of the jamb across the notches 54 and to the 65 plates 57 the hardware is secured. Screws 58

may be passed through one or more additional holes 59 in the plates 57, or the door stop, (see Figures 11 and 12), into the frame 21, to supplement the fastening of the flanges 52 and clips 34.

70 From the above description it will be apparent that the frames 21 are set up and the walls built around them. Later the jambs 22 are fixed in the recesses 29 in the frames, having been previously fitted with the necessary 75 hardware. The hand of door can be easily and quickly changed by removing the jambs originally installed and substituting therefor jambs of the desired formation. These changes in no way mar the building or require any change in the walls or frames proper.

80 Figures 4, 10 and 11 show the invention embodied in a doorway with a single action door, while Figure 12 shows the invention embodied 85 in a doorway with a double action door. Other types of construction could, of course, be employed, if desired.

In place of a sheet metal jamb a wood jamb 60 can be mounted in the recess 29 of the 90 frame 21, as illustrated in Figures 13, 14, 15 and 16. The rear face of the jamb 60 is transversely slotted at 61 to receive retaining straps 62, the ends 62 of which are formed to provide flanges 64 spaced from and parallel 95 to the main portion of the straps. The straps 62 are so located that they will engage the clips 34 in the recess 29, and thus fix the jambs 60 into place.

100 It will be noted that by virtue of this invention, the frame or combination buck and trim can be made commercially in quantity, permitting the stock production of fixed sizes and installation. The hardware requirements, and thickness, hand and type of door, 105 whether hung on butts or hinges or mounted on floor checking hinges, and whether single or double acting, need not be considered in making up the frame 21.

110 While certain embodiments of this invention have been shown and described, applicant is not limited thereto, since it is obvious that other embodiments can be made without departing from the spirit and scope of this invention as set forth in the following claims. 115

Having thus set forth my invention, what I claim as new and for which I desire protection by Letters Patent is:

1. A building construction comprising a 120 frame having a longitudinal recess, clips projecting outwardly from the base of said recess, and a jamb in said recess; said jamb having flanges which engage said clips to fix, said jamb removably to said frame.

125 2. In a building construction including a frame, around which building walls are built, said frame comprising upright members having longitudinally extending recesses therein, and longitudinally extending slots in said recesses, anchors projecting at right angles 130

- from said frame and mounted in said slots, whereby the anchors can be adjusted to suit the construction of masonry built around said frame to form said walls.
- 5 3. A building construction comprising a frame having a central longitudinal recess therein, a jamb in said recess, said jamb having flanges, means forming a part of the base of said recess, engaging said flanges to removably fix said jamb to said frame.
- 10

4. A building construction comprising a frame having inwardly flanged side and base walls forming a recess, a jamb in said recess and means formed in one of the walls of said recess to removably secure said jamb to said frame. 15

In testimony whereof I have affixed my signature.

ERNEST T. JOHNSON.
